J. JOHNSTON.

COMBINATION STAPLE PULLER AND WIRE SPlicer.

APPLICATION FILED MAR. 7, 1918.

1,278,673.

Patented Sept. 10, 1918.

UNITED STATES PATENT OFFICE.

JOHN JOHNSTON, OF ANNawan, ILLINOIS, ASSIGNOR OF ONE-HALF TO TOLMAN
EVERETT, JR., OF ANNawan, ILLINOIS.

COMBINATION STAPLE-PULLER AND WIRE-SPlicer.

1,273,673.

Specification of Letters Patent. Patented Sept. 10, 1918.

Application filed March 7, 1918. Serial No. 221,022.

To all whom it may concern:

Be it known that I, JOHN JOHNSTON, a citizen of the United States, residing at Annawan, in the county of Henry and State of Illinois, have invented a new and useful Combination Staple-Puller and Wire-Splicer, of which the following is a specification.

The device forming the subject matter of this application is a wire stretcher or splicer embodying, as incidental features, means whereby staples may be pulled, rods threaded, nuts manipulated, screws driven, and the like.

The invention aims to provide a knock-down wire stretcher of novel form, meaning by "knock-down" that the structure may be taken apart and housed in small compass, when not in use, the construction being such that when the constituent parts of the structure are assembled, the stretcher will exercise its function.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings:

Figure 1 shows in top plan, a device constructed in accordance with the present invention, the same being shown in connection with a pair of wires which are to be stretched or spliced;

Fig. 2 is a side elevation of the implement hereinafter claimed;

Fig. 3 is an end elevation of the crank;

Fig. 4 is a top plan showing a portion of the crank;

Fig. 5 is a fragmental elevation of the crank, wherein parts are broken away and sectioned; and

Fig. 6 is a cross section taken approximately on the line 6-6 of Fig. 5, distant parts being omitted.

Fig. 7 is a perspective view illustrating

the operation of the device when the same is used to pull a staple.

In carrying out the present invention there is provided a crank 1 including a handle 2 and an arm 3 having an offset end 4 terminating in a transverse eye 5, there being a shoulder 6 at the inner extremity of the end 4 and where the latter part connects with the arm 3. Adjacent the shoulder 6, the end 4 is broadened as shown at 7 to receive a recess 8 which tapers toward the eye 5, the recess being concaved in cross section, as shown at 9 in Fig. 6.

The invention comprises an extension 10 including a shank 11 provided adjacent one end with a wire receiving opening 12 and provided at its other end with a transverse head 14 having a point 15 of tapered form.

The numerals 16 and 17 denotes a pair of wires which are to be drawn together and spliced. A loop 18 is fashioned in the wire 16, a loop 19 being formed in the wire 17. The numeral 20 marks a strand of wire, one end of which is fashioned into a loop 21 coacting with the loop 19 of the wire 17. The extension 10 is placed on the top of the loop 18 and the free end of the strand 20 of wire is passed through the opening 12, as shown at 22. The point 15 of the head 14 is received in the eye 5, the head resting on the end 4 of the arm 3. The butt end of the head 14 is engaged behind the shoulder 6 and fits in the recess 8. In this way, the extension 10 is assembled with the crank 1 securely, but without employing clamping or holding means of any sort, other than those integral parts of the elements 1 and 10 which have been described hereinbefore.

The extension 10 may now be rotated by means of the crank 2, whereupon the strand 20 of wire will be wrapped around the shank 11 of the extension, the loops 19 and 18 being drawn together, and the wires 16 and 17 being tightened. After the wires 16 and 17 have been drawn together to the desired extent, the crank 1 is detached from the extension 10, and the extension 10 is swung around in a direction at right angles to the strand 20, the portion of the strand which has been wrapped around the shank 11 being now unwrapped from the shank and being twisted around the strand 20. By the procedure above outlined, wires 17 and 16 will be drawn together and spliced. The splic-

ing and tightening operation may be carried out in a different manner, if desired, but the tool forming the subject matter of this application will be found to be of peculiar utility in connection with the specific method of splicing above described.

The extension 10 preferably is in the form of a hammer, the shank 11 being supplied at one end with a claw 25 whereby nails may be drawn. The shank 11 is provided with a rectangular opening 23, so that the member 10 may be used as a wrench if desired. Further, the shank 11 may be supplied with thread cutters 24. The point 15 of the head 14 may be used for withdrawing a staple S from a post P as shown in Fig. 7, and the butt end of the head 14 comes into operation when the member 10 is used as a hammer. If desired, the extremity of the handle 2 of the crank 1 may be fashioned into a screw driver 26.

Owing to the fact that the point 15 is tapered and is received in the eye 5, and since the butt end of the head 14 is engaged behind the shoulder 6 and is received in the recess 8, the crank 1 is connected with the extension 10 securely but detachably, it being possible to rotate the extension 10 by means of the crank 1 and it being equally possible, to separate these parts without difficulty, and without resorting to the use of tools of any kind. When the tapered point 15 is received and wedged in the eye 5, and when the butt end of the head 14 coöperates with the shoulder 6 and the recess 8, the parts may be manipulated substantially as one piece, but they may be separated without difficulty if proper relative movement between them, with this specific end in view, is brought about.

Having thus described the invention, what is claimed is:

1. A knock-down wire stretcher comprising a crank embodying an arm provided at one end with a transverse eye; and an extension including a shank having wire engaging means and provided with a transverse head

having a point, the shank being disposed substantially at right angles to the arm, the head being supported on the arm, and the point being received in the eye.

2. A knock-down wire stretcher comprising a crank embodying an arm provided at one end with a transverse eye; and an extension including a shank having wire engaging means and provided with a transverse head having a point at one end, the shank being disposed substantially at right angles to the arm, the head being supported on the arm, the point being received in the eye, and the arm having a shoulder behind which the other end of the head is received.

3. A knock-down wire stretcher comprising a crank embodying an arm provided at one end with a transverse eye; and an extension including a shank having wire engaging means and provided with a transverse head having a point at one end, the shank being disposed substantially at right angles to the arm, the head being supported on the arm, the point being received in the eye, and the arm having a longitudinal recess wherein the other end of the head is received.

4. A knock-down wire stretcher comprising a crank embodying an arm provided at one end with a transverse eye; and an extension including a shank having wire engaging means and provided with a transverse head having a point at one end, the shank being disposed substantially at right angles to the arm, the head being supported on the arm, the point being received in the eye, the arm having a shoulder behind which the other end of the head is received, the arm being provided with a longitudinal recess located adjacent the shoulder, and the other end of the head fitting laterally into the recess.

In testimony that I claim the foregoing as my own, I have hereto affixed my signature in the presence of two witnesses.

JOHN JOHNSTON.
